UNITED STATES PATENT OFFICE.

ARTHUR E. JONES, OF SYRACUSE, NEW YORK, ASSIGNOR TO THE O. M. EDWARDS COMPANY, INC., OF SYRACUSE, NEW YORK, A CORPORATION OF NEW YORK.

SECTIONAL CABINET.

1,285,209.

Specification of Letters Patent. Patented Nov. 19, 1918.

Application filed August 29, 1916. Serial No. 117,425.

To all whom it may concern:

Be it known that I, ARTHUR E. JONES, a citizen of the United States, and a resident of Syracuse, in the county of Onondaga and 5 State of New York, have invented a certain new and useful Sectional Cabinet, of which the following is a specification.

This invention relates to sectional cabinets, and has for its object a particularly 10 simple and efficient locking means for the movable elements, as the drawers or other movable parts of the cabinet, and a thin flat unit carrying the lock operating means, which unit is adapted to be placed between 15 any two sections or above and below any one of the sections, and the lock operating means carried thereby coupled with the locking mechanism of the adjacent sections; and the invention consists in the novel 20 features and in the combinations and constructions hereinafter set forth and claimed.

In describing this invention, reference is had to the accompanying drawings, in 25 which like characters designate corresponding parts in all the views.

Figure 1 is an elevation of three of the sections of my cabinet showing the unit which carries the lock operating means interposed between two of the regular sections 30 which contain drawers or the movable parts to be locked.

Fig. 2 is an enlarged sectional view taken on the plane of line 2—2, Fig. 1.

Fig. 3 is an inverted plan view, partly in section and partly broken away, of the thin flat unit showing the operating means for the locking mechanism.

Fig. 4 is a sectional view taken on the plane of line 4—4, Fig. 2.

Fig. 5 is a fragmentary detail view of the locking mechanism shown in Fig. 4.

This cabinet comprises generally, sections provided with movable parts as drawers, mechanism carried by the sections for locking the drawers, each locking mechanism including means for coupling said mechanism with the mechanisms of adjoining sections, and a unit carrying only the operating means for the locking mechanism of all the 45 various units, this unit being interchangeable with any of the drawer containing sections and placeable between, or above or below any of the regular drawer containing sections, said operating means including

parts for coupling said means to the drawer 55 locking mechanism of the adjoining sections so that the drawer locking mechanism of all the sections can be actuated by the operating means in this unit.

I have here shown my invention as embodied in a sheet metal sectional filing cabinet, each of the sections of which is provided with drawers. Obviously, instead of drawers, other movable parts may be provided and the term drawer is used throughout the specification and claims for the sake of brevity and convenience, but it will be understood that this invention is not limited to the use of drawers, but that any other movable parts may be used instead of drawers.

1, 2 and 3 designate regular sections, each section being shown as provided with two drawers 4 and as including a body or box open at its front side and having the front 75 margins 5, 6, 7 of its top, sides and bottom, bent in angular relation thereto to form a marginal facing around the open front side of the box. The front margins 5, 6 of the top and sides are bent into the box and that 80 of the bottom downwardly at 7 out of the box.

Linings 8 extend from the margins 6 parallel to the sides, to the rear wall and support guides 10 for the drawers. Said linings are formed with angularly arranged parts 11 at their rear ends provided with openings in which the locking bolt to be described is guided. The sections 1, 2, 3 are 85 locked together in any suitable manner 90 so that when they are placed in position one cannot be lifted off the other until its locking means is unlocked. This locking means and the manner in which the sections 1, 2, 3 95 interlock may be of any suitable construction, and form no part of this invention.

The opening at the front end of each section is divided into the drawer spaces by the strip 12, and drawer guides, which are paired with the guides 10 extend rearwardly from opposite edges of this strip.

The downturned front margin 7 together with corresponding flanges or margins 13 and 14 on the sides and back of the box form a shallow cavity 15 on the lower 105 side of each section while the upper side of the top of each section is flat.

As here illustrated, the means for lock-

ing the drawer 4 comprises a rock shaft 16 extending vertically of each section in the rear of the drawers, and a bolt 17 operated by the rock shaft 16 and having means as hooks 18 for interlocking with the drawers, the hooks extending into slots 19 in the rear ends of the drawers and interlocking with said rear walls of the ends of the slots. Each hook has an inclined or ratcheting surface 20 which causes the bolt to be pressed to the right so that the hook can ratchet or latch into operative engagement with the drawer, after the rock shaft is in its locked position and a drawer that has remained partly out, is pushed in.

As here shown, the rock shaft is provided with rock arms 21, 22 at its opposite ends, one of these rock arms as 21 being located within the box near the top and having a crank pin 23 extending through an arc-shaped slot 24 above the flat top. The other rock arm 22 is located at the lower end of the rock shaft 16 in the cavity 15 and has a slot 25 for receiving the pin 23 of the rock arm 21 of the adjoining unit or of a similar rock arm on the operating shaft.

The bolt 17 moves across the rear ends of the drawers and is guided in openings 26 formed in the angular pieces 11 of the linings 8. The motion of the rock shaft 16 is transmitted to the bolt by eccentric means as a rock arm mounted on the rock shaft 16. As here shown, the motion of this rock shaft is transmitted to the bolt 17 in one direction through a spring 28, Figs. 4 and 5, which permits the bolt to be moved in a retrograde direction after the rock shaft 16 has been moved into locked position and a drawer, which was partly out when the shaft 16 was operated, is moved to its completely closed position, as before explained.

As here shown, this spring 28 is interposed between a fixed shoulder 29 in the channel of the bolt 17 and a shoulder 30 on a slide 31 movable in said channel, the slide 31 having a portion 32 extending through the spring 28 and sliding in a suitable hole in the shoulder 29. The body of the slide 31 engages the bottom of the channel of the bolt 17 and is provided with a pin 33 extending through a slot 34 in the bottom of said channel, the pin 33 securing the slide to the bolt 17. The eccentric means on the rock shaft 16 is here shown as a rock arm 35 having a crank pin 36 pressing in one direction against a shoulder 37 on the slide 31 and in the opposite direction against a shoulder 38 on the bolt, the latter shoulder 38 being at one end of a slot 39, in the bottom of the channel of the bolt 17.

As here shown, the shaft 16 extends through the slot 39, this slot having a jog therein at one end of which the shoulder 38 is located. The slide 31 is provided with a tail 40 extending beyond the shoulder 37

and normally abutting against the shoulder 38.

The arrangement of the shaft 16, bolt 17, slide 31 and rock arm 35 is such that when the rock arm rocks to the left, as in Fig. 4, 70 the pin 36 presses against the shoulder 37 and moves the slide 31 and the bolt 17 as a unit to the left, the motion being transmitted through the spring 28. However, in case a drawer is not entirely closed so that the motion of the bolt 17 is obstructed, the spring 28 will be compressed and remain compressed until the drawer is entirely closed, when the spring 28 will press the bolt 17 to the left to its locked position. The spring also permits the bolt to ratchet or latch as previously explained. Movement of the rock shaft 16 to the right presses the pin 36 against the shoulder 38, thus moving the bolt 17 to its unlocked position.

41 designates what for convenience might be termed the locking unit as it carries the operating mechanism for the locking mechanism of the regular sections. This locking unit comprises a plate-like section insertible between, or on top of, or under, any of the regular drawer containing sections, and lock operating mechanism carried by the plate and including means for coupling said means to the lock mechanism of the units and an operating member arranged parallel to the plate and having a handle exposed on the front edge of the plate.

As here illustrated, the plate-like section 41 has its margins arranged in angular relation to form a shallow cavity on one side, as the lower side of the plate, the other or upper side being flat.

As here shown, the operating means comprises an operating rock shaft 42 extending vertically at the rear end of the plate-like section 41, a manually operated member 43 having a handle 44 exposed at the front edge of the unit 41, means connecting the member 43 to the rock shaft 42 and a key 110 operated lock 45 coacting with the member 43.

The rock shaft 42 is arranged to come into alignment with the shafts 16 of the adjoining units and extends at a right angle 115 to the general plane of the unit 41 and is provided with rock arms 46 and 47 similar to the rock arms 21, 22, the rock arm 46 having a pin 48 extending through the arc-shaped slot 49 in the unit 41 for entering 120 the slot of the rock arm 22 of the adjacent regular unit, and the rock arm 47 being arranged to receive in its slot the pin 23 of the rock arm 21 of the adjoining unit.

The rock shaft 42 is journaled at its ends 125 in suitable bearings formed in the upper and lower flanges of a channel iron 50 fitted into the rear end of the section 41 below the top plate.

The operating member 43 extends in a 130

plane parallel to the general plane of the plate-like unit and extends at its front end through the down-turned margin at the front edge of the plate, and the motion of 5 the member 43 is transmitted to the operating shaft 42 by means of a bell crank lever 51 pivoted at 52 to a bracket 53 depending from the top plate of the section 41, one arm of the lever being pivoted at 54 to the rear 10 end of the member 43 and the other arm being pivoted at 55 to one end of a link 56 which is pivoted at its other end at 57 to the rock arm 47.

The member 43 is guided in its movement 15 in a bracket 58 depending from the top of the unit 41 and the inward movement thereof is against the compression spring 59.

The key operated lock 45 may be of any 20 form, size and construction, and includes a bolt 60 coacting with the member 43. The lock has a key hole 61 exposed on the front side of the section 41. When the lock 45 is 25 unlocked, the member 43 is moved forwardly automatically by the spring 59, thus rocking the operating shaft 42, the motion of which is transmitted to the shafts 16 for unlocking the drawers or other movable elements of the regular sections.

When the member 43 is pressed inwardly 30 until locked by the bolt 60 of the lock 45, the motion is transmitted through the operating shaft 42 to the rock shaft 16 of the locking mechanism of the regular units.

By reason of the plate-like unit 41 carrying 35 the operating means for the locking mechanisms of the regular sections, the lock operating means can be placed in any desired position and does not have to be placed or built into a regular section, and hence can 40 be shifted without changing the relative positions of the regular sections.

What I claim is:

1. In a sectional cabinet, the combination 45 of sections having movable members associated therewith, locking mechanism for locking the members from movement, and a plate-like section insertible between any two of the former sections and having lock operating mechanism including coupling means arranged to connect said lock operating mechanism and the locking mechanism of the sections on opposite sides of the plate-like section, substantially as and for the purpose described.

2. A sectional cabinet comprising a section 55 having a drawer therein, a lock for the drawer, and means on opposite sides of the section for coupling the lock to lock operating mechanism, a plate-like section mountable on either of said opposite sides of the former section, and lock operating mechanism carried by the plate-like section and including an operating member, and connections operated by said member extending on 60 opposite sides of the plate-like section for

connection with either of the coupling means of the former section, substantially as and for the purpose described.

3. A sectional cabinet comprising a section having a drawer therein, a lock for the 70 drawer, and means on opposite sides of the cabinet for coupling the lock to lock operating mechanism, a plate-like section mountable on either of said opposite sides of the former section, and lock operating mechanism carried by the plate-like section and including a shaft extending at an angle to the general plane of said plate-like section and having means at its opposite ends for connection with either of the coupling means of 80 the former section, and an operating member carried by the plate-like section and extending parallel to the general plane of said plate-like section, and having a handle exposed on one edge thereof, substantially as 85 and for the purpose specified.

4. A sectional cabinet comprising a section including a box having a drawer therein, the box being flat on one side and having its opposite side depressed forming a shallow cavity, a lock for the drawer, said lock being located in the box and having portions thereof extending through said flat side, and another portion located in the cavity, a plate-like section flat on one side and 90 having its margins arranged to form a shallow cavity on the opposite side, and lock operating mechanism carried by the plate-like section in the cavity thereof and including portions extending beyond the flat side 95 of the plate-like section, and portions located in the cavity, both portions being for connection with the coupling means of the former section, substantially as and for the purpose set forth.

5. A sectional cabinet comprising a section including a box having a drawer therein, the box being flat on one side and its other side being depressed forming a cavity, a lock for the drawer, said lock being located 110 in the box and having a portion thereof extending through said flat side, and another portion located in the cavity, a plate-like section flat on one side and having its margins arranged to form a shallow cavity on 115 the opposite side, and lock operating mechanism carried by the plate-like section in the cavity thereof and including a rock shaft located in the cavity and arranged at an angle to the plane of the plate-like section 120 and having coupling means at one end extending beyond the flat side of the plate-like section, and coupling means at its other end located in the cavity of said section, for connection respectively with said portions 125 of the lock of the former section, substantially as and for the purpose specified.

6. A sectional cabinet comprising a section including a box having a drawer therein, the box being flat on one side and its 130

- other side depressed forming a cavity, a lock for the drawer, said lock being located in the box and having portions thereof extending through said flat side, and another portion located in the cavity, a plate-like section flat on one side and having its margins arranged to form a shallow cavity on the opposite side, and lock operating mechanism carried by the plate-like section in the cavity thereof and including a rock shaft located in the cavity and arranged at an angle to the plane of the plate-like section and having coupling means at one end extending beyond the flat side of the plate-like section, and coupling means at its other end located in the cavity of said section for connection respectively with said portions of the lock of the former section, and an operating member located in the cavity and connected to the rock shaft and extending parallel to the plane of the plate-like section through the angular front margin thereof, substantially as and for the purpose set forth.
7. A locking unit for sectional cabinets comprising a plate-like section, and lock operating mechanism carried by the section and including coupling means extending on opposite sides of the plate-like section, and an operating member extending parallel to the plate-like section and having a handle exposed at the edge of said section, in combination with sections of the cabinet between which the plate-like section is inserted, the cabinet sections having lock mechanism including portions for coacting with said coupling means of the plate-like section, substantially as and for the purpose described.
8. A locking unit for sectional cabinets comprising a plate-like section having its margins arranged in angular relation to the major part of said section thereby providing a section flat on one side and with a shallow cavity on the opposite side, and lock operating mechanism located in the cavity and having coupling means extending beyond the flat side of the section, and additional coupling means located in the cavity, and an operating member located in the cavity and connected to the coupling means, the operating member extending through the angular margin of the section, in combination with sections of the cabinet between which the plate-like section is inserted, the cabinet sections having lock mechanism including portions for coacting with said coupling means of the plate-like section, substantially as and for the purpose specified.
9. A sectional cabinet comprising sections having drawers therein, each section having a lock for the drawer therein, said lock including means for coupling the same to the coupling means of adjacent sections, a plate-like section placeable above or below any one of the former sections, and lock operating

mechanism carried by the plate-like section and including means for coupling said mechanism to the locking means of the adjacent sections, substantially as and for the purpose set forth.

10. A sectional cabinet including sections, each having a drawer therein, and mechanism for locking the drawer including a rock shaft having coupling means at its opposite ends for connection with complementary coupling means on the rock shafts of the locking means of adjoining sections, a plate-like section, a rock shaft carried by the plate-like section and provided with means at its opposite ends for coupling the same respectively to opposite ends of the rock shafts of the former sections, and an operating member for rocking the shaft of the plate-like section, substantially as and for the purpose described.

11. A sectional cabinet comprising sections having drawers therein, and means for locking the drawers including rock shafts associated with the sections respectively, each rock shaft having at its ends rock arms exposed on opposite sides of the section, the arm at one end being formed with a pin and the arm at its other end being formed with a slot for receiving the pin on the rock arm of the adjacent section, substantially as and for the purpose set forth.

12. A sectional cabinet comprising sections, having drawers therein, means for locking the drawers including rock shafts associated with the sections respectively, each rock shaft having at its ends rock arms exposed on opposite sides of the section, the arm at one end being formed with a pin and the arm at its other end being formed with a slot for receiving the pin on the rock arm of the adjacent section, a plate-like section, an operating rock shaft carried by the plate-like section and arranged at an angle to the plate-like section, the rock shaft being provided with rock arms at its ends, one of the rock arms having a pin and the other having a slot similar to the pin and the slot of the rock arms of any one of the former sections, and an operating member for rocking said operating shaft, said member being carried by the plate-like section and movable in a plane parallel to said plate-like section, and having a handle exposed at the edge of said section, substantially as and for the purpose described.

13. A sectional cabinet comprising sections, drawers movable in the sections, and means for locking the drawers comprising a rock shaft having a rock arm at one end formed with a pin projecting at one side of the section, and a rock arm at the other end of said shaft formed with a slot, the section being provided with a cavity in which the latter rock arm is located, the pin of one rock arm and the slot of the other rock arm

being arranged to coact with the slot and the pin of the rock arms of adjacent sections and the pin of each section extending into the cavity of the adjacent section, substantially as and for the purpose set forth.

14. In a cabinet, a body, a drawer in the body, and mechanism for locking the drawer including a rock shaft, a sliding bolt extending at an angle to the rock shaft, eccentric means on the rock shaft coacting with the bolt to move the same, and spring means interposed between the eccentric means and the bolt whereby the rocking movement of the rock shaft in one direction is transmitted to the bolt through said spring means, and the bolt is permitted to move in a retrograde direction relatively to the rock shaft, against the action of the spring means, for permitting the locking bolt to ratchet into engagement with the drawer upon the closing of the drawer after the rock shaft has been locked from movement, substantially as and for the purpose set forth.

15. A cabinet comprising a body, a drawer in the body, and means for locking the drawer including a sliding bolt having means for interlocking with the drawer, a slide, a spring interposed between the slide and the bolt, and means pressing against the slide in one direction and tending to compress the spring and acting against the bolt in the opposite direction, substantially as and for the purpose described.

16. A cabinet comprising a body, a drawer in the body, and means for locking the drawer including a sliding bolt having means for interlocking with the drawer, a slide, a spring interposed between the slide and the bolt, and a rock shaft arranged at an angle to the bolt and having eccentric means bearing against the slide and tending to transmit the motion in one direction to

the bolt through the spring, and pressing directly against the bolt to move the same in the opposite direction, substantially as and for the purpose specified.

17. A cabinet comprising a body, a drawer in the body, and means for locking the drawer including a sliding bolt extending transversely of the drawer and having means for interlocking with the drawer, the bolt being in the form of a channel iron and having a shoulder therein, a slide located in the channel and having a shoulder opposed to the former shoulder, a spring interposed between the shoulders, and means for operating the bolt including a part acting in one direction against the slide, and in the opposite direction against the bolt, substantially as and for the purpose set forth.

18. A cabinet comprising a body, a drawer in the body, and means for locking the drawer including a sliding bolt extending transversely of the rear end of the drawer and having means for interlocking with the drawer, the bolt being in the form of a channel iron and having a slot, a shoulder in the channel thereof, a slide located in the channel and having a shoulder opposed to the former shoulder, a spring interposed between the shoulders, and means for operating the bolt comprising a rock shaft extending through the slot in a direction at an angle to the movement of the bolt and having eccentric means acting on one direction against the slide and in the opposite direction against the bolt, substantially as and for the purpose described.

In testimony whereof I have hereunto signed my name at Syracuse, in the county of Onondaga and State of New York, this 24th day of May, 1916.

ARTHUR E. JONES.
